UNITED STATES PATENT OFFICE

2,509,074

BEACH STICK

Gene Reiley, Wynnewood, Pa.

Application August 27, 1947, Serial No. 770,827

2 Claims. (Cl. 220—18)

1

This invention relates to a combined container and stand therefore and, more particularly, to a device adapted to be used on the beach or lawn to support any variety of articles.

An object of the invention is to provide a device of the character hereinafter described which may be conveniently transported by hand and may be stuck into the sand or ground to act as a depository for food, sun glasses, bathing caps, toys, cards, or any number of articles. It is well known that bathers have difficulty in locating small articles left on the sand or in preventing food, such as sandwiches, from being contaminated by sand or dirt, and it is my object to provide a simple, convenient and relatively inexpensive device which may be easily handled and stored to overcome these objections.

With these and other objects in view, all of which will become apparent from the following description and from the drawing, reference is had to the accompanying drawing in which

Figure 1 is a front elevation of a device constructed in accordance with my invention;

Fig. 2 is an enlarged view taken on the line 2—2 of Fig. 1;

Fig. 3 is a cross sectional view taken on the line 3—3 of Fig. 2; and

Fig. 4 is a detailed view taken on the line 4—4 of Fig. 1.

Referring more particularly to the drawing, my device consists of a shaft 10 which may be made of simple tubing with a pointed casting 11 at its lower end. Mounted on the shaft 10 is a container 12 and a combined handle member and rack 14. By means of novel construction, my device is assembled of a minimum number of parts and with a minimum number of fastening elements. The container element consists of two pieces; one forming the four walls thereof and another the bottom. The walls of the container are formed from a single piece of sheet material 15 which is bent upon itself to form the front, sides and back, with the back ends overlapping at 16. The top of the back 17 is bent at right angles at 18 to form a flange 19. The bottom member 20 is a sheet of material bent upon itself to form flanges 21 and 22 at the back and front and side flanges 23. Handle 14 consists of a strip of material bent upon itself to form a handle with depending ends

25. In assembly, the bottom 20 is fastened to the pre-formed sheet 15 by means of rivets 26 at the front and two sides. The handle member is in turn attached to the container by means of rivets 27 extending through the handle member 14 and the flange 19, as shown in Fig. 4. By this means, the handle member acts to strengthen the walls of the container 12 since it keeps the back members 17 in place at the top. A single screw 28

2

is then inserted through the flange 21 at the bottom to the adjoining or overlapping back member 17 and the shaft 10. This operation takes place, of course, after the depending members

5 25 are inserted within the shaft. Screw 28 not only holds the back members together and to the shaft, but prevents the withdrawal of the depending members 25 of the handle section 14 from the shaft 10.

10 It will be appreciated that a great many articles may be carried in such container which, with its shaft, forms a convenient carrier preferably about the length of a walking stick. When inserted in the sand, it functions as a container 15 while the handle member 14 can be used as a rack for towels, robes or other articles. For purposes of identification and decoration, stripe 30 may be extended around the shaft.

It will be seen that I have provided a very useful 20 device, simple in construction, and novel in its assembly but which, nevertheless, will be strong and durable.

I claim:

1. A device of the character described comprising a shaft, a handle member mounted on top of said shaft, said handle member consisting of a strip of material bent upon itself having its ends positioned in said shaft, a container consisting of a strip of material bent upon itself to form front, 30 side and rear walls, said rear walls overlapping at the back thereof and having flanges fastened to said handle member, a bottom member for said container, and a fastening element fastened through said bottom member, said overlapping 35 rear walls and into said shaft to position said container and handle member with relation to the shaft.

2. In a device of the character described, a hollow shaft, a combined rack and handle having its 40 ends positioned in said shaft, a container made of sheet material bent upon itself to form front, and side walls, and overlapping to form a rear wall, flanges on said rear wall, fastening means extending through said handle member into said flanges, 45 a bottom fastened to said container, and a screw extending through said bottom, through said overlapping back wall into said shaft to position said combined handle and rack member and said container on said shaft.
